UNITED STATES PATENT OFFICE

JAMES E. TRAINER AND IVAR L. LANGVAND, OF BARBERTON, OHIO, ASSIGNORS TO THE BABCOCK & WILCOX COMPANY, OF BAYONNE, NEW JERSEY, A CORPORATION OF NEW JERSEY

ECONOMIZER TUBE SUPPORT

Original application filed January 11, 1928, Serial No. 245,970. Divided and this application filed June 20, 1929. Serial No. 372,332.

This invention relates to an economizer in which the ends of the tubes are connected by return bends in such a manner that the joints are outside of the economizer walls.

5 This is a division of our application Serial No. 245,970, filed January 11, 1928, (Patent 1,818,769, granted August 11, 1931) and will be understood from the description in connection with the accompanying drawings, in

10 which

Fig. 1 is a vertical section through an illustrated embodiment of the invention.

Fig. 2 is a horizontal section partly broken away, taken along the line 2—2 of Fig. 3, 15 and Fig. 3 is a section taken along the line 3—3 of Fig. 2.

In the drawings, reference character 1 indicates rows of economizer tubes. The end walls 3 of the economizer are provided with 20 holes through which the tubes 1 extend. A row of holes 4 is provided in supports near the middle of each side wall of the economizer through which holes the ends of supports 5 for the tubes 1 extend. A casing 6 is spaced 25 a short distance from the walls of the economizer and return bends 8 are located inside the casing and outside of the economizer walls, and connect the ends of each row of tubes to the ends of the next row, the tubes being 30 staggered with respect to each other, as indicated in Fig. 3.

The holes 4, through which the ends of the supports 5 extend, are provided in columns 9 along the sides of the economizer. The supports 35 5 for the tubes 1 are made up of pairs of strips 10 and 11 side by side, that are provided with notches 12 along their upper edges. The notches 12 are somewhat deeper than half the diameter of the tubes 1, and one end 40 of each notch 12 in the strip 10 is provided with an overhanging lip 13 and the other ends of the notches 12 in the strip 11 are left with a similar overhanging lip, so that, when the strips are moved in opposite directions 45 with the tubes 1 in the notches 12, the tubes will be clamped in place so as to prevent lateral movement of the tubes with respect to the supports 5.

The strips 10 and 11 are provided with 50 transverse rectangular openings 14, so that

when a wedge 15 is driven into the openings 14, the strips 10 and 11 will be moved in opposite directions and clamp the tubes 1. Bolts 16 are provided for retaining the strips 10 and 11 in their clamping position after the 55 wedge 15 has been inserted.

The supports 5 which are preferably located near the middle of the tubes 1, prevent the tubes from sagging down. The supports 5 can be readily unloosened to permit removal 60 of any injured tube.

Plates 17 and side members 18 close the spaces beyond the ends of the supports 5 and prevent gases from escaping through the openings 4 through which the supports 5 extend. 65

We claim:—

1. In an economizer, a row of tubes, a support for intermediate portions of said tubes, said support extending loosely through the 70 sides of said economizer, and means to prevent leakage beyond the ends of said support.

2. A support for tubes comprising a plurality of bars movable longitudinally with respect to each other and each having tube receiving notches along a margin, each of said notches having a straight side and a curved side with the straight sides of the notches in one bar corresponding to the curved notches of the adjacent bar. 75

3. A support for tubes comprising a plurality of bars movable longitudinally with respect to each other and each having tube receiving notches along a margin, and means to adjust said bars longitudinally with respect to each other and maintain them in their adjusted position with tubes clamped in said notches. 85

4. A support for tubes comprising a plurality of bars movable longitudinally with respect to each other and each having tube receiving notches along a margin, and means to adjust said bars longitudinally with respect to each other and maintain them in their adjusted position with tubes clamped in said notches, said means comprising a wedge and a bolt. 90

5. In fluid heat exchange apparatus, a casing having openings along one side, rows of spaced fluid conducting tubes extending 100

- through the casing and being in heat exchange contact with hot gases passing through the casing, tube spacers each comprising relatively movable clamping strips inserted through the openings and between the rows of tubes, tube clamping formations on the strips adapted to have locking and embracing engagement with the tubes when the strips are moved lengthwise relative to each other, and means accessible from the exterior of the casing for moving the strips relative to each other and for locking them in the tube clamping relation into which they are moved.
6. In fluid heat exchange apparatus, a casing having openings along one side, rows of spaced fluid conducting tubes extending through the casing and being in heat exchange contact with hot gases passing through the casing, tube spacers each comprising relatively movable clamping strips inserted through the openings and between the rows of tubes, tube clamping formations on the strips adapted to have locking and embracing engagement with the tubes when the strips are moved lengthwise relative to each other, and means accessible from the exterior of the casing for moving the strips relative to each other and for locking them in the tube clamping relation into which they are moved, and a removable cover extending over the strip ends for preventing the escape of the hot gases from the casing.
7. In fluid heat exchange apparatus, a casing having an opening along one side, a row of spaced fluid conducting tubes extending through the casing and being in heat exchange contact with the hot gases passing through the casing, a tube spacer comprising relatively movable clamping strips inserted through the opening, tube clamping formations on the strips adapted to have locking and embracing engagement with the tubes when the strips are moved lengthwise relative to each other, and means for moving the strips relative to each other.
8. In fluid heat exchange apparatus, a casing having openings along one side, rows of spaced fluid conducting tubes extending through the casing and being in heat exchange contact with hot gases passing through the casing, tube spacers each comprising relatively movable clamping strips inserted through the openings and between the rows of tubes, tube clamping formations on the strips adapted to have locking and embracing engagement with the tubes when the strips are moved lengthwise relative to each other, a wedge passing through the strips for moving the strips relative to each other, and means for locking the strips in the tube clamping relation into which they are moved.
9. A row of spaced members, a multi-part spacer extending transversely of said members, marginal formations on parts of the spacer presenting spaced marginal notches wide enough to allow the spacer to be moved bodily transversely of the row to position the members in the notches, and means for moving some of said formations to cause the members to be tightly clamped and embraced by the formations.
